CAR ROOF

Karl F. Nystrom, Milwaukee, Wis., assignor, by mesne assignments, of one-half to P. H. Murphy Company, New Kensington, Pa., a corporation of Pennsylvania and one-half to Standard Railway Equipment Manufacturing Company, a corporation of Delaware

Application March 10, 1937, Serial No. 130,107

7 Claims. (Cl. 108—5.4)

My invention relates to a roof construction more especially applicable to railroad freight cars of the welded steel car type; the invention having for its object the provision of uniform steel elements constituting roof sheets, carlines, roof side plates, stiffeners, and running-board, arranged to present surfaces whereby the respective elements may be readily united or welded together into a roof unit and this preassembled and integrally 5 united roof then applied to the car; the roof-sheets and carlines being formed to provide attaching portions whereby the roof unit may then afford a continuous integral union with the steel car body.

One object of the invention is the provision of a roof unit composed of simple elements consisting of flat sheets and simple pressings without need for complicated dies or complex operations for interfitting between roof elements or roof and car.

Another object of the invention is the provision of what may be termed a self-sustaining roof, namely a roof in which the need of a ridge pole is eliminated due to the reinforcing and supporting relation between the roof proper and the running board; the various elements and their associated relation affording the requisite structural stiffness to permit safe handling of the roof unit from assembly jig to the car or to place of storage as the case may be.

The aforementioned objects and the advantages inherent in the invention will all be readily comprehended from the detailed description of the accompanying drawings wherein:

Figure 1 is a top plan of my improved roof unit, an intermediate portion and one end being broken away.

Figure 2 is a cross-sectional perspective view taken on the line 2—2 of Figure 1, as viewed by the arrows.

Figure 3 is a sectional view taken on the line 3—3 of Figure 2 and viewed as indicated by the arrows.

Figures 4 and 5 are similar detail cross-sectional views illustrating modifications of running-board construction and arrangement.

My invention contemplates the fabrication of a roof unit from a comparatively few preformed elements of rather simple construction comprising 50 roof sheets 10, carlines 11, running-board 12, roof side plates 13, and stiffener elements 14.

The precut roof sheets are preferably of uniform predetermined length which enables the successive sheets to exactly adjoin or abut immediately on a carline. In car construction, the

carlines are uniformly spaced lengthwise of the car and the roof sheets 10 are cut to a convenient uniform length so as to overlap a prearranged number of carlines as illustrated for example in Figure 1 and at the right-hand end of the illustration where a roof sheet 10 is shown extending from the right end of the roof to the approximate longitudinal center of the fourth carline from that car end and indicated in dotted lines at 11. The successive or next adjacent roof sheet 10 extends from this fourth carline (reading from the right hand end of Figure 1) to the eighth carline from the right, and so on to the opposite or left hand end of the roof which is not shown but which end is in every way similar to the right hand end disclosed in Figure 1.

It will, of course, be understood that the particular length of roof sheets mentioned is merely employed as an exemplification and that the roof sheet may be of any desired length adapted to 20 overlap any given number of carlines and therefore I do not wish to be understood as limiting myself to the precise arrangement illustrated.

The roof sheets as shown consist of flat rectangular sheets whose adjoining edges are preferably spot welded to the subjacent carline which might be termed the splicing carline, as indicated at 15 in Figure 3. It will be understood, however, that if desired the roof sheets could be attached to the carline by plug welding.

It has also been found advisable, in addition to welding the roof sheets to the subjacent carline, also to weld the adjacent edges of the successive roof sheets to each other by a continuous weld as shown at 16, thereby ensuring a rigid 35 and weather proof juncture.

The ends of the roof are finished off with any suitable pressed shape which best suits the steel end and which is secured in such manner that the integrally united roof forming elements may 40 be readily applied to the car as a unit and be firmly secured to the car ends.

The carlines 11 consist of sheet metal pressed into inverted channel form and the marginal edges of the sides of the channel provided with laterally disposed flanges 17 (see Figure 3) which tend to reinforce or stiffen the carlines. The carlines preferably taper toward the ends which is accomplished by having the depth of the channels gradually diminish from the portion 45 intended to be located at the longitudinal center line of the car roof toward the ends of the carlines and therefore toward the sides of the car.

In order to simplify the operation of formation and also provide for convenience in manip- 55

ulation, I prefer to construct the carlines in two identical sections or halves which are adapted to be placed in end to end or abutting relation and these two sections welded together, coincident with the longitudinal center line of the roof, as indicated at 18 in Figure 2; the weld extending throughout the top, sides and lateral flanges of the carline, thereby providing a very rigid or stiff structure.

10 The ends of the carlines are securely welded to the roof side plates, one of which is disclosed at 13 in Figure 2; and the roof side plates, which are of form to closely conform to the body side plate partly shown at 19 in Figure 2, are then 15 securely fastened or welded to the car or body side plates 19 of the car. The two side plates, namely the roof side plate 13 and the body side plate 19 are then secured or simultaneously welded to the side posts of the car body; one 20 of the side posts being shown at 20 in Figure 2.

25 The roof sheets 10, as seen in Figure 2, extend beyond the ends of the carlines and overlap the roof side plate 13 and a further union between the roof unit and the car sides is provided by a continuous weld, indicated at 21, extending lengthwise of the car whereby the roof sheet, the roof side plate and the body side plate are simultaneously joined together.

30 In order to properly stiffen the roof sheets between the carlines I provide the under side of the roof sheets, intermediate of the successive carlines, with the stiffener elements 14 which preferably are in the nature of angle bars disposed in directions lengthwise of the roof. I prefer to employ a pair of these angle bar stiffeners arranged in spaced relation intermediate of the car sides and the longitudinal center line of the car, on each side of the longitudinal center. These angle stiffener bars 14 preferably are spot 40 welded to the roof sheets 10.

45 My improved roof unit also involves the running-board section 12 which extends lengthwise from end to end of the roof and consists of sheet metal of predetermined width to straddle the ridge of the roof and extend a sufficient distance to opposite sides of the longitudinal center line of the roof as shown in Figure 2. The longitudinal edges of the running-board sheet are bent downwardly and the free marginal edges are then 50 preferably bent laterally as shown at 22 in Figure 2 into parallel relation with the roof sheets 10 to which the laterally disposed flange portions 22 are intimately united by means of a continuous weld along the edge of the running board 55 at 23.

The flanges 22 on opposite sides of the running board when intimately united with the roof sheets act as longitudinal stiffeners which extend full length of the car roof.

60 As shown in Figure 2, the roof sheets 10 may terminate beneath the downwardly bent longitudinal edges of the running-board section because the running-board section being intimately united at its flanged sides with the roof sheets 65 will constitute a roof section across the ridge, uniting the roof sheets on opposite sides of the longitudinal center line, thus obviating the necessity and expense of roof sheets along the center line.

70 The center of the running board 12 is also welded at 24 to the successive carlines 11, namely coincident with the welded joint 18 between the carline halves.

75 By reason of the continuous running board sheet—somewhat in the nature of a shallow

channel plate—and its intimate connection with the roof sheets and with the respective carlines, the use of the usual ridge pole is obviated as the necessary stiffness for the roof along the center line is provided by the combination running-board and roof section 12. The center of the running-board 12 preferably is welded to the carlines by means of plug welds.

80 The running-board section 12 is preferably provided with an outer rough surface obtained in any suitable manner for the purpose of affording proper footing for the trainmen. The running-board 12 may be applied in sheets or sections of any convenient length and they may consist of equal sections on opposite sides of the roof ridge and joined together at the center by welding.

20 The channel shaped carlines are provided with a wood filler or strip 25, see Figure 3, which affords suitable means for fastening the inside wood finish of the car in place, as for example the ceiling element 26 which may consist of plywood. The wood strip 25 may be fastened in the carline in any suitable manner as for example by bolts, not shown in the drawings.

25 In Figures 4 and 5 I illustrate alternate constructions of the running-board for providing additional stiffness to the ridge or center of the roof. The running-board 12^a shown in Figure 4 is provided along the center line with a downwardly 30 presented ridge or rib 27 which may be provided by either depressing the running-board sheet along the longitudinal center or it may be produced by uniting two similar channel sections 28, 28, and welding the abutting sides of the two 35 sections together as well as to the subjacent carlines 11. The other or outer longitudinal sides of these sections 28, 28 are also disposed downwardly and thence laterally into the flange portions 29, which extend parallel and flush with the 40 roof sheets 10 to which the flange portions 29 are welded as in the construction previously described.

45 The alternate form shown in Figure 5 consists of an inverted channel like sheet 12^b substantially similar to the form shown in Figure 2, except that the lower face of the running-board section at the longitudinal center is provided with supporting member 30.

50 This member may be in the nature of an angle bar or strip with one longitudinal edge welded to the running-board sheet while the other side or leg of the bar or strip extends parallel with the carlines to which it is welded. This bar or strip 30 not only supports the center of the running board but also reinforces it.

55 These alternate running-board constructions, like in the previously described construction, constitute roof sections and also constitute stiffeners and eliminate the necessity of ridge poles as heretofore employed.

60 The welding at the center of the running-board sections to the carlines is preferably in the nature of plug welds through the running board and on to the carlines, a form of weld which could also be used in welding the roof sheets to the carlines; although any suitable type of weld as taught by shop practice may be employed.

65 In the assembly of a complete roof, a sufficient number of carlines suitably spaced are first 70 formed and provided. The roof sheets are then welded to the carlines and the roof side plates then attached to the ends of the carlines, as heretofore described. The previously formed running board is then applied in sections of any conveni- 75

ent length and welded to the roof sheets and to carlines as described.

The ends of the roof are finished off with any suitable pressed shape which best suits the steel end and in such manner that the assembled roof may be readily applied as a unit to the car body.

The top of the running board section of the roof may either be roughened or a suitable tread plate may be applied to provide a non-slip surface.

In application, the two side plates, namely the body side plate and the roof side plate may be joined by what is known as chain welds at points between the side posts of the car body and the 15 chain welds spaced to provide sufficient strength.

It will be understood that any suitable methods of welding may be employed in assembling my improved roof unit which consists of simple sections or elements comprising flat sheets and simple shapes or pressings requiring no complicated dies in their fabrication; elements or sections which also do not require coping to fit other portions or elements of the roof or car.

Furthermore, by employing the longitudinal running-board section as an integral part of the roof structure, the necessity for separate conventional types of running boards is obviated; while the inclusion of the running board as an integral section or part of the roof unit also eliminates 30 the necessity of employing the usual ridge pole.

The respective elements of the roof are preferably united by suitable welding as hereinbefore stated, although riveting or any suitable method of integrally uniting the various elements into a 35 complete roof unit may be employed.

The specific form or construction of the various elements illustrated and the methods of uniting these elements as herein described are believed to be the simplest embodiment of the invention which has been described in terms employed merely for purposes of description and not as terms of limitation, as modifications are possible and may be made without, however, departing from the spirit of my invention as expressed in 45 the accompanying claims.

What I claim is:

1. In a car roof, a series of carlines, roof sheets extending longitudinally of the car to span a series of carlines and secured to each carline by welding, said sheets extending transversely of the car from the eaves to a point spaced from the ridge, and running board sections complementary to said roof sheets arranged in a higher plane and provided with depending edge portions terminating in base flanges welded to the upper edge portions of said sheets, said running board sections being also centrally attached to the carlines at the ridge.

2. In a car roof, a series of carlines, roof side plates welded to the ends of said carlines, roof sheets extending longitudinally of the car to span a series of carlines being welded to each carline, the eaves portion of said sheets extending over and secured to a portion of said roof side plate and the opposite edge portion of said sheet being spaced from the ridge, running board sections complementary to said roof sheets arranged in a higher plane with depending edge portions terminating in base flanges resting upon and welded to the upper edge portions of said roof sheets, said running board sections being also centrally attached to said carlines.

3. In a car the combination with frame side plates, of a roof comprising a series of carlines, roof side plates welded to the ends of said carlines

and being of a cross section to fit the side plates of the car frame, roof sheets extending longitudinally of the car to span a series of carlines and secured to each carline by welding, the abutting ends of adjacent sheets being disposed on top of a carline and welded thereto and to each other, and running board sections complementary to said roof sheets arranged in a higher plane with depending edge portions terminating in base flanges welded to the upper edge portions of said sheets and also centrally attached to said carlines, said running board sections also spanning a series of carlines with the abutting edges of adjacent sections offset longitudinally of the car from the abutting edges of adjacent roof sheets.

4. In a car the combination with frame side plates, of a roof comprising a series of carlines each formed of complementary sections extending on opposite sides of the ridge and welded to each other, each section being of inverted channel cross section with outwardly extending base flanges and being tapered in depth from ridge to eaves, roof side plates welded to the ends of said carlines and of a cross section to fit over the side plates of the car frame, roof sheets extending longitudinally of the car to span a series of said carlines and secured thereto by welding, the edge portions of said sheets overlapping portions of said roof side plates and welded thereto, and the opposite edges of said sheets being spaced from the ridge, and running board sections complementary to said roof sheets arranged in a higher plane and having depending edge portions terminating in base flanges welded to the upper edge portions of said sheets, said running board sections being also centrally welded to said carlines.

5. In a car the combination with frame side plates, of a roof comprising a series of carlines each formed of complementary sections extending on opposite sides of the ridge and welded to each other, each section being of inverted channel cross section with outwardly extending base flanges and being tapered in depth from ridge to eaves, roof side plates welded to the ends of said carlines and of a cross section to fit over the side plates of the car frame, roof sheets extending longitudinally of the car to span a series of said carlines and secured thereto by welding, stiffening flanges for said roof sheets welded to the underside thereof and extending between carlines, the edge portions of said sheets overlapping portions of said roof side plates and welded thereto, and the opposite edges of said sheets being spaced from the ridge, and running board sections complementary to said roof sheets arranged in a higher plane and having depending edge portions terminating in base flanges welded to the upper edge portions of said sheets, said running board sections being also centrally welded to said carlines.

6. In a car roof, a series of carlines, roof side plates welded to the ends of said carlines, roof sheets extending longitudinally of the car to span a series of carlines being welded to each carline, the eaves portion of said sheets extending over and secured to a portion of said roof side plate and the opposite edge portion of said sheet being spaced from the ridge, running board sections complementary to said roof sheets arranged in a higher plane with depending edge portions terminating in base flanges resting upon and welded to the upper edge portions of said roof sheets, said running board sections being also centrally attached to said carlines, and car

body side plates having upper portions of inverted channel cross section to which said roof side plates are attached.

7. In a car roof, a series of carlines, roof side plates welded to the ends of said carlines, roof sheets extending longitudinally of the car to span a series of carlines being welded to each carline, the eaves portion of said sheets extending over and secured to a portion of said roof side plate and the opposite edge portion of said sheet being spaced from the ridge, running board sections complementary to said roof sheets arranged

in a higher plane with depending edge portions terminating in base flanges resting upon and welded to the upper edge portions of said roof sheets, said running board sections being also centrally attached to said carlines, and car body side plates having their upper portions of inverted channel cross section with the rounded corner between the top and inner side thereof, said roof side plates being of similar cross section to fit upon said top and inner side and being secured thereto by welding. 5

KARL F. NYSTROM. 10
